UNITED STATES PATENT OFFICE.

JOSEPH ACITO AND PAUL TIMEN, OF NEW YORK, N. Y., ASSIGNORS TO STAP CO., OF NEW YORK, N. Y., A CORPORATION OF NEW YORK.

CLASP.

Application filed August 17, 1922. Serial No. 582,381.

To all whom it may concern:

Be it known that we, JOSEPH ACITO and PAUL TIMEN, citizens of the United States, residing at New York city, in the county of New York and State of New York, have invented certain new and useful Improvements in a Clasp; and we do hereby declare the following to be a full, clear, and exact description of the invention, such as will enable others skilled in the art to which it appertains to make and use the same.

The invention relates to fastening means designed chiefly for personal wear, such as necklaces, and one of the main objects is the provision of a clasp which is secure against casual opening, thereby preventing the loss of the article fastened thereby.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figures 1 and 2 are obverse and reverse views, respectively, of a clasp embodying the invention,

Figure 3 is a central longitudinal section thereof,

Figure 4 is a transverse section,

Figure 5 is a detail perspective view of the socket member, and

Figure 6 is a detail perspective view of the catch member.

Corresponding and like parts are referred to in the following description and designated in the several views of the drawings by like reference characters.

The clasp comprises essentially a head 1 and a catch 2. The head 1 is hollow and is provided at one end with an attaching ring 3 and is provided in its back with an elongated opening or slot 4.

Said head or socket member 1 has an abutment 5 secured in its hollow midway of the ends and transverse to said slot.

The catch 2 is elongated and partakes of the nature of a bar and is provided at one end with a crosshead 6 wider than the

bar and said slot and at its opposite end with an engaging ring 7 and a hook 8. The necklace or other part to be fastened has one end engaged with the ring 3 of the head 1 and the other end engaged with the ring 7 of the catch member 2. The parts of the clasp are fastened by positioning the catch member 2 at right angles to the slot 4 and passing the crosshead 6 through said slot 4 to the left of the abutment 5, after which the member 2 is given a one-quarter turn to dispose it in slot 4 resting on abutment 5 and with cross head 6 in abutment therewith after which pressure is exerted upon the outer end of said catch member to cause the hook 8 to engage the adjacent end of the head 1 by a snap action. It will thus be understood that when the clasp is fastened, the catch member 2 is seated in the slot 4 and its crosshead 6 is disposed within and crosswise of the elongated slot 4. A clasp constructed in accordance with the invention is not liable to open accidentally because of the twofold movement required to release the catch member, one of such movements requiring disengagement of the hook 8 from the head 1 and the other movement necessitating the turning of the head 1 at a right angle to the recess or channel 5 to permit of the crosshead 6 clearing the elongated slot 4.

What is claimed is:

1. A clasp having a head provided with an elongated slot, a catch for disposition in said slot through turning movement relatively to the head, a cross head on said catch, said cross head adapted for disposition within the slot to resist displacement of the catch from said slot in a direction transversely of the head, and an abutment located out of said slot and within the head for engagement by said cross head to limit longitudinal movement of the latter in one direction.

2. A clasp having a head provided with a wall having an elongated slot therethrough, a catch for disposition in said slot through turning movement relatively to the head, and means to resist displacement of the catch from said slot movable into overlapping relation with the under surface of said wall through said movement, and means at a distance from and supplementing the said means to fasten the catch to the head.

3. A clasp having a head provided with an elongated slot, a catch for disposition in said

slot through turning movement relatively to the head, means to resist displacement of the catch from said slot movable to utile position through said movement, and means supplementing the said means to fasten the catch to the head, consisting of coacting snap means on said catch and head.

4. A clasp having a hollow head provided with an elongated slot, an abutment within the head midway of the ends of said slot and disposed transversely of the slot, a catch for disposition in said slot through turning movement relatively to the head, a cross head on said catch adapted to overlap the

interior wall of the head and adjacent said slot, said catch adapted to rest on said abutment and said cross head adapted to intimately engage the same, the catch at one end having a hook, and said hook adapted to snap on to said head.

In testimony whereof we affix our signatures in presence of two witnesses.

JOSEPH ACITO.
PAUL TIMEN.
